CLAIM

The ornamental design for a medical gauze patch, as shown and described.

DESCRIPTION

FIG. 1 is a front perspective view of a medical gauze patch showing my new design according to a first embodiment; FIG. 2 is a rear perspective view thereof; FIG. 3 is a front elevational view thereof; FIG. 4 is a rear elevational view thereof; FIG. 5 is a top plan view thereof; FIG. 6 is a bottom plan view thereof; FIG. 7 is a magnified view of the portion shown and designated in FIG. 6; FIG. 8 is a left-side elevational view thereof; FIG. 9 is a right-side elevational view thereof; and, FIG. 10 is a front elevational view of the medical gauze patch, according to a second embodiment.

In FIG. 10, the medical gauze patch is shown with two symbolic breaks in its length and width, defined by breakaway lines. The appearance of any portion of the medical gauze patch between the breakaway lines forms no part of the claim. The breakaway lines also form no part of the claim.
